CABINET CONSTRUCTION

Leonard H. Darbyshire, Detroit, Mich., assignor to
 Borg-Warner Corporation, a corporation of Illinois

Application February 4, 1937, Serial No. 124,076

1 Claim. (Cl. 220—9)

This invention relates to cabinet construction and has particular reference to certain new and useful improvements in heat insulated cabinets and method of constructing the same.

For purposes of illustration, the invention is shown as being embodied in a refrigerator cabinet of the household type, which comprises a sheet metal outer shell adapted to form a support and enclosure for a heat insulated provision compartment and a machine or apparatus compartment. The shell may be constructed of several suitably formed metallic panels and a base, which preferably are fixedly secured together, such as by welding, so as to form a casing for enclosing the insulation, provision tank and apparatus, and which casing constitutes a support therefor.

A principal object of the invention is to provide a new and improved form of heat insulated cabinet which is more simple in construction than cabinets of this type as heretofore known, and which cabinet, because of the simplicity of its construction, can be manufactured at a lower cost.

Another object of the invention is to provide a new and improved construction for supporting the provision tank in a refrigerator cabinet.

Another object of the invention is to provide an improved construction for more efficiently insulating the provision tank of a refrigerator cabinet.

Another object of the invention is to provide an improved construction for heat insulated cabinets wherein the insulation material is enclosed in such a way as to be protected from exposure to moisture.

Another object of the invention is to provide an improvement in cabinet constructions of the type disclosed herein, wherein the shell of the cabinet is so constructed and arranged as to form a frame upon which the interior parts of the cabinet are supported.

Another object of the invention is to provide a new and improved method of constructing cabinets of the type illustrated herein.

Other objects and advantages of the invention will be apparent from a consideration of the following specification taken in conjunction with the accompanying drawings, of which there are four (4) sheets, and wherein:

Fig. 1 is a front elevational view of a refrigerator cabinet embodying my invention;

Fig. 2 is a vertical sectional view through the upper front corner of the cabinet shown in Fig. 1

and taken in a plane on the line 2—2 of Fig. 1, looking in the direction of the arrows;

Fig. 3 is a horizontal sectional view through the front and rear side corners of the cabinet shown in Fig. 1 and taken in a plane on the line 3—3 of Fig. 1, looking in the direction of the arrows;

Fig. 4 is a vertical sectional view, taken in a plane on the line 4—4 of Fig. 1 and illustrating that part of the front of the cabinet which separates the provision compartment from the machine compartment;

Figs. 5 and 6 are vertical sectional views taken in planes on the lines 5—5 and 6—6 respectively, of Figs. 2 and 4, looking in the direction of the arrows and illustrating in section the details of construction of the cabinet at the upper and lower side corners of the provision compartment;

Figs. 7 and 8 are vertical sectional views taken in planes on the lines 7—7 and 8—8 respectively, of Figs. 5 and 6, looking in the direction of the arrows and illustrating certain details of the cabinet construction at the upper and lower rear corners of the provision compartment;

Fig. 9 is a plan view of one side of the base and illustrating the relationship thereof to one of the side walls of the cabinet, said side walls being shown in section;

Fig. 10 is a view similar to that of part of Fig. 3 and illustrating a modified form of construction;

Fig. 11 is a perspective view of the sides and top of a modified form of shell for the cabinet illustrated in Fig. 1;

Fig. 12 is a plan view of a part of a blank of metal illustrating a step in the process by which the shell illustrated in Fig. 11 may be formed;

Fig. 13 is a perspective view of the blank illustrated in Fig. 12, but at a later step in the process;

Fig. 14 is a perspective view of the sides and top of a modified form of shell for the cabinet illustrated in Fig. 1;

Fig. 15 is a perspective view of one of the panels of the shell illustrated in Fig. 14;

Fig. 16 is a section illustrating one manner in which the two panels of the shell illustrated in Fig. 14 might be arranged and secured relative to each other;

Fig. 17 illustrates a different manner in which the two panels of the shell illustrated in Fig. 14 might be joined together at their adjoining edges at the top of the cabinet; and

Fig. 18 is a vertical section illustrating the

manner in which the side panels are secured to the base of the cabinet.

In Fig. 1 there is shown in front elevation a refrigerator cabinet embodying my invention and having a door 20 which closes the access opening to the provision compartment and a door 22 which closes the front access opening to the machine compartment. The outer covering of the cabinet may be provided by a shell indicated generally at 24 and which may be formed by securing together a pair of side panels 26, top panel 28, back panel 30, and a base 32. These panels or parts may be formed out of sheet metal. One of the side panels 26 may be formed, as illustrated in Fig. 3, to provide a covering or surface for a side of the cabinet, and which extends around the vertical corners at the front and the rear of the cabinet so as to cover portions of the front and rear walls contiguous to said side wall and which extends from the bottom of the cabinet to approximately the level of the upper edge of the access opening in the front wall of the cabinet. At the rear, the side panel is provided with a return flange 34, and at the front, the side panel 26 is provided with an inwardly extending flange 36. The top edge of the side panel 26 is provided with an offset 38. The side panel 26 for the other side of the cabinet may have the same section as that illustrated in Fig. 3 but must be formed as the reverse thereof and is provided with a like return flange 34 at the rear thereof, an inturned flange 36 at the front thereof, and an offset like offset 38. Those portions of the side panels 26 which cover the front and rear vertical corners of the cabinet and portions of the front and rear walls of the cabinet may be considered as integral flanges 40 of the side panels 26. As will be observed in Fig. 3, the front flanges 40 extend around to the edge of the access opening for the provision compartment and cover that portion of the front wall of the cabinet disposed laterally of the access opening and the door 20 so that each of the side panels 26 completely covers those portions of the sides of the cabinet from the vertical edge of the access opening around to the back of the cabinet where the space between the back flanges 40 is covered by the back panel 30, which extends from the same top level as the upper edge of the side panels 26, down to a level just below that of the provision compartment where the bottom edge of the back panel 30 is turned inwardly to form a flange 42, which extends between the returning flanges 34 and the side panels 26, thereby leaving the space at the back of the cabinet and below the flange 42 open. The top panel 28 is formed as a cap having depending side flanges 44, a depending rear flange 46, and a depending front flange 48, the front flange having a return flange 50, which extends between the inturned flanges 36 of the side panel members 26 and at the upper edge of the access opening to the provision compartment. The top panel 28 may be joined to the side panels 26, as illustrated in Fig. 5, by welding the lower edge of the flanges 44 to the offsets 38 so as to provide a substantially smooth and continuous outer surface for the shell, and the top panel 28 may be secured to the back panel 30 by welding depending flange 46 of the top panel 28 to the upper edge of the back panel 30, as illustrated in Fig. 7. The back panel 30 may be secured to the side panel 26 by welding the side edges of the back panel 30 to the rear flanged portions 40 of the side panel members 26, as illustrated in Fig.

3. The bottom edges of the side panels 26 are secured to the base 32, as illustrated in Fig. 18, wherein it may be observed that the bottom edges of the side panels 26 are provided with a return flange 52 which receives the rim 54 of the base 32. The rim 54, the flange 52 and the opposite portion of the panel 26 may be secured together by welding so that the side panel members 26 are supported by the base 32.

The provision compartment is formed by a sheet metal tank 56 of rectangular shape, formed of metal or any other suitable material enclosed on all sides, except at the front, where the inner periphery of the tank 56 about the opening is formed to provide a throat 58 and a flange 60, by means of which flange 60 the tank 56 is secured in position in the cabinet.

A rectangular frame indicated generally at 62 and comprising a top horizontally disposed member 64, a pair of vertically disposed side members 66, and a horizontally disposed bottom member 68 is arranged within the shell 24 at the front and adjacent the upper part thereof so as to define a door opening. The inturned flanges 36 of the side panels 26 and the inturned flange 50 of the top panel 28 are provided with a series of openings, by means of which the frame 62 may be nailed within the shell 24 and to the side and top panels thereof. The frame 62 preferably is formed by securing the parts thereof rigidly together and such frame is inserted in position within the shell 24 after the shell has been formed and provided with suitable finish, such as lacquer or porcelain. The under side of the bottom member 68 of the frame 62 may be provided with one or more plates 10 suitably secured thereto and which plates 10, together with the inturned flange 42 of the back panel member 30, provide a seat for a slab 72 of wood or other material which forms a transverse wall across the shell and defines the upper wall of a machine compartment disposed therebelow. The space above the wall 72 and below the top panel 28 and between the side and rear walls and the door 20 defines a space within the shell 24 within which the provision tank 56 is disposed.

After the frame 62 and the slab 72 are arranged in place within the shell 24, the inside of the space above the slab 72 is lined with slabs or packages 74 of heat insulating material. The heat insulating material may comprise any suitable insulation which is wrapped or covered with a waterproof or water-resisting material so as to keep moisture away from the insulation and such slabs may be formed as rectangular shaped packages so that they may be readily inserted in place and completely fill the space between the provision tank 56 and the outer shell of the cabinet. The insulation material preferably is preformed so that it will readily fit within the space available in the shell 24.

The packages of insulation may be arranged as follows: One or more slabs 74 may be stood on end upon the wall 72 and adjacent each of the side panels 26. The insulation material adjacent the side panels 26 should have a vertical edge seated against the vertical member 66 of the wood frame 62 and should extend to the rear of the cabinet and into close proximity with the rear flanges 40 of the side panel members 26. Another slab 74 of insulation may be horizontally arranged upon the wall 72 and between the slabs 74 which are disposed against the side panel members 26. At the rear of the cabinet,

one or more slabs 74 of insulation may be supported upon the slab 74 which is horizontally disposed upon the wall 72 and against the back panel member 30 and so as to extend between the slabs 74 at the sides of the cabinet. The slabs 74 of insulation at the top of the cabinet are supported upon the top edges of the side and rear slabs of insulation so that after all the insulation has been arranged, the space within the shell above the wall 72 will be completely lined with insulation except for the door opening.

The upper outer corners of the wall 72 may be cut away as at 76 and around the periphery thereof so as to provide a space which may be filled with a sealing material such as tar or any other substance which will seal the wall 72 to the adjoining side walls or parts of the shell 24 so as to prevent substantially the circulation of air or moisture through the joints between the various sections of the walls. Certain adjoining edges of the slabs 74 of insulation and parts of the cabinet are provided with tar or some other sealing material such as at the points indicated by the reference character 78 so that the slabs of insulation are bonded or sealed together and to the frame 62 and slab 72 so as to prevent circulation of air through the joints between the various slabs of insulating material. The tar or sealing material may be applied to the space formed by the removed corners 76 of the wall 72 before the insulation is installed and may be applied to the insulation either before or after the slabs are arranged in place, if the insulation material is of such nature that the slabs may be deformed slightly for the purpose of applying the sealing material.

After the insulation has been arranged in place, tank 56 may be inserted within the remaining space and there should be a good snug fit between the tank 56 and the insulation material. The flange 60 of the tank is provided with a series of holes by means of which the tank may be secured to the frame 62, such as by a series of screws 80. Strips 82 of material may be secured to the inner periphery of the frame 62 for bridging the space between the flanges 50 and 36 of the shell and the flange 60 of the tank 56. Such strips may be secured to the frame by a series of screws 83. The strips 82 may be formed of wood covered with a suitable waterproof material to form a throat lining for the access opening to the provision tank 56. The outer surface of the bottom member 68 of the frame 62 may be covered by a removable metallic strip or panel 84 having a finish like the exterior of the shell 24 and secured in place by one or more screws 86. The panel 84 need not be welded or otherwise integrally secured to the shell 24, but simply removably secured to the member 68. The heads of the screws 86 may be utilized for hanging the door 22 of the machine compartment. It will be observed in referring to Fig. 1, that the door of the machine compartment extends downwardly so as to cover the front of the frame 32 and to simulate the appearance of a base for the cabinet. As the side panels 26 extend down to the bottom of the cabinet, as illustrated in Fig. 18, no separate base is provided for the cabinet, but the base 32 may be provided with four short legs 88 at the corners of the cabinet so that the bottom edges of the panels 26 will be supported just clear of the floor upon which the cabinet sets.

The door 20 may be supported by a pair of hinges 90 which may be secured to the frame 62.

The base 32 may comprise a pair of end members 92 connected by a pair of front and rear side rails 94 and provided with four brackets 96 by means of which a condensing unit may be removably supported upon the base 32. The base 32 preferably is formed as a unit and out of metal stampings before being welded to the remainder of the shell 24.

The door 20 may be formed in any suitable manner and provided with insulating material and the inner face of the door adjacent the periphery thereof may be provided with a continuous resilient gasket 98 for sealing the door to those portions of the front wall of the cabinet about the access opening to the provision compartment.

The joint between the top panel 28 and the side panels 26 may be provided by welding the adjoining portions of these panels together and finishing or polishing the weld so that the joint between the panels is hardly noticeable. As the top panel 28 extends from the edge of the access opening upwardly over the front wall of the cabinet, thence over the top wall of the cabinet and thence down over the top rear corner, as well as over the top side corners and the four corners formed at the juncture of the side and top walls, the shell may, after being finished, have the appearance of being formed out of a continuous piece of metal and will have a smooth and continuous surface which may readily be kept clean.

The welding of the side, top and rear panels, and the base together, provides a rigid shell which acts as a frame and supports all of the parts of the cabinet and the apparatus arranged therein. It will be observed that there is no metallic connection between the outer shell 24 and the tank 56 and that the tank 56 is supported entirely by the frame 62 which is secured to the front of the shell 24. The return flanges 34 at the back of the cabinet serve to stiffen the side panels 26. It will be observed that with this construction, the necessity of a separate independent and rigid frame work is eliminated. While it may be observed that some of the slabs 74 of insulating material are spaced from parts of the outer shell 24, this is due to the shape of the outer shell and the rounded corners thereof, and there is no necessity of, or particular advantage resulting from, having an air space between the slabs 74 of insulation and the outer shell 24 at certain parts of the cabinet.

In Fig. 10 there is illustrated a modified form of the invention wherein the interior surfaces of the shell 24 are coated with a thin film of a water-proofing material such as a plastic, rubber, or some material which may be applied by spraying so as to deposit a thin and continuous film of material over the entire surface on the inside of the shell, as well as the exposed surfaces of the wood frame 62.

In Fig. 10 there is illustrated a horizontal section through the rear side corner of the cabinet, such as disclosed in Fig. 3. In Fig. 10 it will be observed that the film 100 of plastic material extends continuously over the joints between adjoining panels such as the joints between the back panel 30 and the rear flange 40 of the side panel 26. The interior of the shell preferably would be provided with the film of water-proofing material prior to the installation of the slabs 74 of insulation and this film

100 of water-proofing material may extend over all of the interior surface of the shell 24 above the wall 12 as well as over the surfaces of the wood frame 62. Preferably wood frame 62 might be provided with a film or coating 100 of water-proofing material prior to insertion into the shell 24. On account of the continuity of the coating 100 and the resistance thereof to the passage of air or moisture therethrough, the coating 100 would provide an additional protection for the insulation material. The coating 100 may be of some material which will dry after application so that the slabs 14 of insulation will not adhere to the inside of the shell.

In Figs. 11 to 13 inclusive, there is illustrated a modified form of shell construction wherein the top and sides of the shell are shown as being constructed of a single blank of metal. While only the top and sides of the shell are illustrated in Figs. 11 to 13, it is contemplated that the remainder of the shell and the cabinet construction may be like that illustrated in Figs. 1 to 10 and 18.

In Fig. 12 there is shown a plan view of a 25 portion of a flat blank 120 of metal, which blank is of such dimensions so as to provide a covering for the top and side walls of the cabinet, those portions of the front wall disposed outwardly of the access opening, all of the corners at the rear of the cabinet and certain portions of the rear wall adjacent the side and top walls of the cabinet. Fig. 12 shows the manner in which the blank 120 is cut so that the blank may be bent to form the corners between the 30 top, front, rear and side walls at one side of the cabinet. The corners at the other side of the cabinet may be formed from a similar cutting of the blank. When the blank 120 is flat, a portion thereof along the front edge, is removed as at 122 so that when the blank is folded or bent about the axis 124, the edges formed by removing the metal at 122 will meet as illustrated at 126, so that after welding or otherwise securing the edges of the cut together a smooth and continuous corner will be provided between the front, top, and side walls of the shell at one side thereof. Similarly, before the blank 120 is bent, a portion thereof along the rear edge thereof is removed as at 128, so that when the blank 120 is folded, a smooth and continuous corner will be provided between the top, side and rear walls of the shell at one side thereof.

After removing metal from the blank as at 122 and 128, the blank 120 may be bent along the lines 130, 132 and 134, so as to provide a rear flange 140, a front flange 142, and a return flange 136. The return flange 136 is adapted to be arranged like the flanges 36 and 50 illustrated in Figs. 1 to 10; that is, to provide a means by which the front of the shell may be secured to the frame 62. The blank 120 may be folded along the line 130 so as to provide substantially a right angle corner 131 at the rear of the cabinet, whereas the blank may be bent about the line 132 so as to provide a rounded corner such as illustrated at 144 at the front of the cabinet. The rear corner may be formed similar to the front corner if desired. The bend along line 124 is illustrated as providing a round corner between the top and sides, but other corners may be used, in which event the shape of the removed portions 122 and 128 would be different. After the blank 120 has been bent to form the top wall 146, side walls 148, the flanges 142 which cover the front

wall outwardly of the access opening, and the rear flanges 140, the base and the back cabinet may be added in a manner similar to that illustrated in Figs. 1 to 10 and the exterior surface of the shell can then be provided with a suitable finish such as porcelain or lacquer after which the remaining parts of the cabinet may be assembled, as illustrated in Figs. 1 to 10.

In Figs. 14 to 17 inclusive, there is shown a further modification of the invention wherein the top and side walls are provided by two panels which meet at the center of the top. A pair of panels 150 may be formed in accordance with the process set forth in connection with Figs. 11 to 13 inclusive, to provide a portion 152 for covering one side of the cabinet, a portion 154 for covering one half of the top of the cabinet, flanges 156 for covering parts of the front wall disposed outwardly of the door opening and flanges 158 for covering parts of the rear wall, the portions and flanges being formed so as to provide a continuous surface for covering the corners between the side, front and rear walls. The edge of the panel at the front may be provided with a flange 160 like the flanges 36 and 50 and the edge of the top portion 154 of the panel may be provided with a depending flange 162 so that when the two panels are assembled as illustrated in Figs. 14 and 16, the flanges 162 may be nailed or secured to a frame member 164 and a strip 166 of trim may be removably secured by means of a clip 168 for covering the joint between the two top portions 154 of the panels 150. If the panels 150 are arranged as illustrated in Fig. 16, it may be desirable to provide more framework for the cabinet than is illustrated in Figs. 1 to 10; although when the back panel, the wooden door frame and the base have been assembled with the two panels 150, the two panels 150 will be securely fastened together. However, if it seems desirable, additional framing may be provided. The frame member 164 may be a member which extends under the joint between the two panels 154.

If desired, the two panels 150 may be joined together along the top by a joint such as that illustrated in Fig. 17 wherein the top portion 154 of one of the panels may be provided with an offset 155 so that portions of the two panels may be disposed in overlapping relationship and welded together so as to make the two panels 150 an integral unit similar to the shell illustrated in Fig. 11. In fact the shell made with the two panels as illustrated in Figs. 14 and 15 is similar to the shell made with the single blank as illustrated in Fig. 11 except for the joint at the top between the two panels 150. If a joint like that illustrated in Fig. 17 is utilized, the shell, after being provided with a finished surface, will have the appearance of the shell illustrated in Fig. 11.

The portion of the shell illustrated in Figs. 14 and 15 may be completed in a manner similar to that as set forth in connection with the embodiment of the invention illustrated in Figs. 1 to 10.

While the invention has been described with some detail, it is to be understood that the description is for the purpose of illustration only and is not definitive of the limits of the inventive idea. The right is reserved to make such changes in the details of construction and arrangement of parts as will fall within the purview of the attached claim.

In a refrigerator cabinet, a metal casing, said

casing comprising a pair of side panels having inturned portions at the top rigidly joined together to form the top of the casing, said panels having flanges along each edge thereof forming a portion of the front and rear walls of said cabinet, a rigid frame attached to the inside of the flanges forming the front of said cabinet and bracing the upper portion of said panels, said frame also defining a door opening and providing a support for a door for said opening, a back 10 panel attached to the flanges on the back side

of said first mentioned panels and having an inturned flange extending between the opposite sides of the flanges on said first mentioned panels, a horizontal partition supported between said inturned flange on said back panel and the lower portion of said rigid frame, and an integral base member rigidly attached to the ends of said first mentioned panels and bracing said panel and supporting said cabinet.

LEONARD H. DARBYSHIRE.
